Primary Examiner — Darlington Ly*Assistant Examiner* — Giang Hoang Tran(74) *Attorney, Agent, or Firm* — BainwoodHuang(57) **CLAIM**

The ornamental design for a tracked firefighting vehicle as shown and described.

DESCRIPTION

FIG. 1 is a top, front and left side isometric view of a tracked firefighting vehicle;

FIG. 2 is a bottom, font and right side isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines represent portions of the tracked vehicle that form no part of the claimed design.
